JOSEPH D. DAVENPORT, OF NORTH PROVIDENCE, RHODE ISLAND, ASSIGNOR BY JOHN D. THURSTON, HIS TRUSTEE, TO HIMSELF, HORACE M. CURTIS, AND HENRY MARTIN.

Letters Patent No. 78,069, dated May 19, 1868.

IMPROVED CLOTHES-DRIER.

The Schedule referred to in these Letters Patent and making part of the same.

TO ALL WHOM IT MAY CONCERN:

Be it known that I, JOSEPH D. DAVENPORT, of North Providence, in the county of Providence, and State of Rhode Island, have invented a new and useful Improvement in Clothes-Horses; and I do hereby declare that the following specification, taken in connection with the drawings making a part of the same, is a full, clear, and exact description thereof.

My improvement consists in so combining a number of suitable frames, upon which clothes can be hung, with a common central spindle or foot-stand, that such frames, when the clothes-horse is in use, radiating from such central stand, can be clamped together, and in consequence the clothes-horse can be more conveniently moved, when filled with clothes, along the floor from place to place, without risk of upsetting.

In the drawing, showing my improved clothes-horse in perspective, it will be seen that A A represent a convenient number of side-rails suitable for a clothes-horse, each of which is furnished with a convenient number of horizontal slats or bars, B, for holding articles, which may be hung over them. All of these partial frames so constructed are hinged to a common central spindle or shaft, C, which passes through holes or eyes provided in the ends of the slats. Obviously the axes of these holes or eyes should coincide, and, as the several horizontal bars or slats B are, at their point of connection with the central spindle, placed one above another, they should also be arranged in the frames to which they belong, with such variations of height from the floor respectively as will accommodate this necessity.

In order to clamp these several radial-bars B together, I prefer to surround the central shaft with sections of pipe D furnished with flanges a, which sections of pipe, forming long collars, fill the spaces in the length of the spindle between the sets of bars, and also a similar section occupies the space between the foot of the spindle and the under side of the first bar, or, instead of such collar at this place, a nut may be used. The upper end of the spindle is provided with a screw-thread, and in connection with it is a thumb-nut, E. It is quite apparent that, upon turning the nut E, the several bars can be clamped, so that the whole apparatus, when the radial frames of which it is made up are spread apart, can be moved without danger of the frames folding upon each other.

It is not absolutely necessary, though preferable, to so construct the clothes-horse that the pressure of the thumb-nut shall, by means of the long collars D, be communicated to each of the sets of slats in the series. A washer, held up against the lower slat of the uppermost set by a pin passing through the spindle, would furnish a stationary surface, between which and the thumb-nut the uppermost set of slats would be clamped, and thereby the advantage of my improvement would be obtained, though in a less substantial form.

What I claim as my invention, and desire to secure by Letters Patent, is—

The application of a clamp, E D, to the slats B of a clothes-horse, radiating from a common spindle, substantially as described for the purposes specified.

JOSEPH D. DAVENPORT.
